US00D905059S

(12) **United States Design Patent** (10) Patent No.: **US D905,059 S**
(45) Date of Patent: **** Dec. 15, 2020**

(54) **CARD READER DEVICE**(71) Applicant: **Square, Inc.**, San Francisco, CA (US)(72) Inventors: **Jeremy Martin**, San Francisco, CA (US); **Mani Razaghi**, San Francisco, CA (US); **Joseph Laucks**, San Francisco, CA (US)(73) Assignee: **Square, Inc.**, San Francisco, CA (US)(***) Term: **15 Years**(21) Appl. No.: **29/657,827**(22) Filed: **Jul. 25, 2018**(51) LOC (12) Cl. **14-02**

(52) U.S. Cl.

(57) **CLAIM**

The ornamental design for a card reader device, as shown and described.

DESCRIPTION

FIG. 1 is a front perspective view of a first embodiment of a card reader device;

FIG. 2 is a front perspective view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the card reader device that form no part of the claimed design.

1 Claim, 7 Drawing Sheets
